MORRIS SCHOENFELD, OF RORSCHACH, SWITZERLAND.

EMBROIDERY-FRAME.

1,129,607.

Specification of Letters Patent. Patented Feb. 23, 1915.

Application filed February 12, 1913. Serial No. 748,010.

To all whom it may concern:

Be it known that I, MORRIS SCHOENFELD, a citizen of the United States, residing in Rorschach, Canton of St. Gall, Switzerland, 5 have invented new and useful Improvements in Embroidery-Frames, of which the following is a full, clear, and exact specification.

The object of the present invention is an 10 embroidery frame which is distinguished from the embroidery frames hitherto in use, by the feature that it is composed of two distinct groups of frame members or rods, the frame members or rods of one group 15 being placed upright so as to constitute the lateral parts of the frame and arranged so as to be only movable in a vertical direction relatively to stationary machine frame parts, while the frame members or rods of 20 the other group carrying the fabric constitute the upper and lower parts of the frame and are guided by the members or rods of the first group so as to be movable relatively to them in a horizontal direction.

25 In the accompanying drawing, some constructional examples of the invention are illustrated as follows:

Figure 1 shows a partial front elevation, with certain parts in section, and Fig. 2 a 30 vertical section of a preferred construction in which the embroidery frame is supported adjustable transversely to its stitch motions, that is to say, transversely to the fabric plane; in Fig. 1, some parts have been 35 omitted for the sake of clearness. Fig. 3 shows a modification in which the frame is rigidly mounted on the machine frame. Figs. 4 and 5 show a guide for the frame rods of the one group. Fig. 6 shows in plan 40 view a detail of the mechanism shown in Fig. 1.

Around fixed pivots 1 (Fig. 1) there move supporting bolts 4 which are connected one with another by compulsorily operated elements 2, 3. The embroidery frame is held in a position of equilibrium upon 45 rollers 5 which are placed revolvably and adjustably in the axial direction upon the pivots 4 (Fig. 6), in consequence of the action of a counterweight 6, which, by means of a bar 7 and a lever 8, is guided to move parallel with itself. The rollers 5 are correspondingly supported in suitable tracks 9; these roller tracks 9 are provided with 50 shoulders in front and behind (Fig. 2) in such a manner that they carry the rollers 5

with them along the pivots 4 when a pushing away of the frame from the fabric plane or an approach thereto is effected. These roller tracks 9 are each rigidly connected 60 with a vertical frame rod 12 guided vertically in the guides 10 and 11, and on the other hand, they serve for the guidance of a lower horizontal frame rod 13 in the horizontal direction, and also an upper horizontal frame rod 14 is guided in sockets 15 of the vertical frame rods 12 in the horizontal direction. The horizontal frame rods 13, 14 which form the one group of frame rods consequently participate in the vertical motions of the vertical frame rods 12 forming 65 the other group, but they can also be moved relatively to these latter in the horizontal direction. The up-and-down motion of the embroidery frame, that is of the two groups 70 of frame rods, is effected by means of the bolts 4, by the turning of the wheels 2, while the horizontal relative displacement of the frame rods 13, 14 is effected by the displacement of one of them 75 80 and by a parallelogram lever connection 16, 17, 18 which turns upon the stationary axles 19 and is made compulsory or positive for both horizontal frame rods in like manner. The vertical rods 20 which are rigidly connected 85 with the horizontal frame rods 13 and 14 are for strengthening purposes.

The parts 21, 22, 23, 24 (Fig. 2) are well known parts of the shuttle mechanism (shuttle tracks, shuttle driver bar, shuttle 90 drivers, shuttle board). In the construction shown in Fig. 2 the guides 10, 11 of the frame rods 12 are attached to the shuttle boards 24. These latter are supported by the plungers 25, which are adjustable in 95 bearings 26 on the machine frame 27, so that the entire embroidery frame is transported on the moving-out or forward or backward adjustment of the shuttle tracks upon the parts 25.

The embroidery frame 12, 13, 14, 20 is provided as shown in Fig. 2 with fabric rollers 28, 29, 30, 31 movably supported in the well known manner on the frame parts 13, 14, 20, so as to allow of the displacement of the 105 frame transversely to the fabric plane, but it might also be provided only with stretching devices for the fabric of the well known kind if the fabric rollers were placed outside the fabric frame.

According to Fig. 3 the vertical frame rods 12 are guided in fixed bearings 32 on

100

105

110

the cross bars 27 in a vertical direction. Moreover, the vertical frame rods 12 are so bent over above and below, that a moving out of the shuttle mechanism is possible without 5 a transverse movement of the fabric frame. The guiding of the vertical frame rods 12 is effected as shown in Figs. 4 and 5 by means of movable rollers 33 in such a manner that a displacement can only take place 10 in the axial direction, while any turning motion of the frame rods 12 about themselves is prevented by means of a longitudinal rib 34 on the frame rods 12. The number of the driving points for the vertical and horizontal frame parts or rods is here of no importance. 15

Obviously the arrangement illustrated in the drawing according to which the weight of the frame rests upon the pivots 1 placed 20 below the frame is only shown by way of example.

What I claim is:

1. In an embroidering machine, a stationary machine frame, a fabric frame composed of two separate groups of frame rods, one of which has its frame rods distributed 25 in upright position from distance to distance over the length of the frame so as to constitute side and intermediate frame parts 30 and arranged so as to be only movable in a vertical direction relatively to the machine frame, while the frame rods of the other group carrying the fabric constitute the upper and lower longitudinal parts of the 35 frame and are independently guided by and coupled to the frame rods of the first group so as to be movable relatively to them in one and the same horizontal direction.

2. In an embroidering machine, a stationary machine frame, a fabric frame composed of two distinct groups of frame rods, constituting the upper, lower and lateral parts of the frame, the frame rods of one group being placed upright so as to constitute the 40 lateral parts of the frame and arranged so

as to be only movable in a vertical direction relatively to the machine frame, while the frame rods of the other group constitute the upper and lower parts of the frame, extending 50 over the whole length thereof, and are movably carried by the frame rods of the first group so as to be displaceable relatively to them in a horizontal direction, positive guide rollers being provided for the upright frame rods of the first group. 55

3. In an embroidering machine, a stationary machine frame, a fabric frame composed of two distinct groups of frame rods constituting the upper, lower and lateral parts of the frame, the frame rods of one group being placed upright so as to constitute the lateral 60 parts of the frame and arranged so as to be movable in a vertical direction relatively to the machine frame, while the frame rods of the other group constitute the upper and lower parts of the frame and are movably carried by the frame rods of the first group so as to be displaceable relatively to them in a horizontal direction, adjustable guide means being provided for the upright frame 65 rods of the first group.

4. In an embroidering machine, a machine frame carrying a shuttle board, a fabric frame comprising two distinct groups of members, the frame members of one group being placed upright and movable in the direction of the height, while those of the other group are movably carried by the frame members of the first group so as to be displaceable relatively to them in a horizontal 75 direction, positive guide means being provided on said shuttle board for the upright frame members of the first group. 80

In witness whereof I have hereunto signed my name this 29th day of January 1913, in the presence of two subscribing witnesses.

MORRIS SCHOENFELD.
